UNITED STATES PATENT OFFICE.

CHRISTEN CHRISTENSEN, OF CHICAGO, ILLINOIS, ASSIGNOR TO ELECTRICAL ENGINEERS EQUIPMENT CO., OF CHICAGO, ILLINOIS, A CORPORATION OF ILLINOIS.

DISCONNECTING-SWITCH.

1,394,968.

Specification of Letters Patent. Patented Oct. 25, 1921.

Application filed June 4, 1919. Serial No. 301,718.

To all whom it may concern:

Be it known that I, CHRISTEN CHRISTENSEN, a citizen of the United States, residing in Chicago, in the county of Cook and State of Illinois, have invented a certain new and useful Improvement in Disconnecting-Switches, of which the following is a full, clear, concise, and exact description, reference being had to the accompanying drawings, forming a part of this specification.

My invention relates to disconnecting switches and particularly to disconnecting switches adapted for remote control such as disconnecting switches of the pole top type.

Switches of this general description are particularly adapted for dividing a transmission line into sections to facilitate inspection and repairs. They are usually mounted in the transmission line upon a tower or pole adjacent a power house or sub-station or upon a frame on top of the station in alinement with the conductor to be controlled and are operated or controlled from a distance as by an arrangement of rods and levers extending to a suitable operating handle in a convenient position at the foot of the tower or other supporting structure.

Where considerable current must be carried and particularly where relatively high tension current is involved the matter of providing a quick, positive opening switch presents a very considerable practical difficulty. This is particularly true when the switch is fairly large and heavy. The frictional resistance of the terminals and the weight of the movable switch member in switches of this type is frequently such as to make quick and positive opening a very difficult matter. I propose to overcome such difficulties as this by providing whereby the switch is opened through a changeable leverage, the power for breaking contact being applied through a relatively great leverage to secure a relatively great force and consequently a positive break whereupon the leverage is decreased to increase the speed of the movable switch member toward full open position which is so essential in breaking the electric arc.

A further feature of my invention is the provision of a switch of the above general

type of simple, inexpensive and rugged construction.

A still further feature of my invention is the provision of a switch wherein the controlling mechanism in addition to operating the movable switch element controls auxiliary switching elements for indicating to the operator the exact condition of the switch, namely as to whether the movable switch element is in the open or closed position.

In accordance with the teachings of my invention the live parts of the switch are mounted upon insulators of any known or preferred type, an intermediate insulator being arranged between a plurality of links and adapted to open or close the switch upon the application of a suitable force to either of the links. In this connection another salient feature of my invention appears in the provision whereby the supporting and the operating insulators of the switch are either in direct tension or compression when the switch is operating. There are no torsional stresses to which such insulators have been commonly subjected heretofore.

Further important features of my invention are the provision of an improved switch operating or controlling mechanism characterized by its ability to quickly and positively open the movable switch element and the provision of means for locking the movable switch element in either open or closed positions.

Other features of my invention not hereinbefore set forth will appear from the following detailed description and the claims taken with an inspection of the accompanying drawings in which:

Figure 1 is a side elevational view of a switch constructed in accordance with the teachings of my invention; showing the same as adapted for vertical mounting;

Fig. 2 is a front elevational view of the same;

Fig. 3 is a side elevational view of the switch as adapted for horizontal mounting showing the operating mechanism therefor;

Fig. 4 is an enlarged side elevational view partly in section of the operating mechanism; and

Fig. 5 is the front elevational view of the same.

Referring first to Figs. 1 and 2 of the drawings the upper switch terminal com-

prises a tongue or terminal lug 1, provided with a suitable base 2. The lower or hinge terminal comprises a terminal base 3 having a pair of hinge jaws 4, extending outwardly from the opposite edges thereof. These upper and lower switch terminals are mounted by means of the terminal bases 2 and 3 upon suitable angle brackets 5 and 6. The angle brackets 5 and 6 are mounted 10 in this case upon insulator clamps 7 and 8 of any known or preferred type, although those disclosed in the pending application of Ernest H. Jacobs, Serial No. 274,159, filed January 31st, 1919, have been found to be preferable. The insulator clamps 7 and 8 are supported upon the tops or outer ends of the inclined insulators 9 and 10, the lower ends of which insulators are supported in insulator clamps 11 and 12, mounted upon 20 the inclined pedestals 13 and 14, which inclined pedestals 13 and 14 are in turn mounted upon the channel iron mounting base 15. The mounting base 15 is adapted to be mounted either in vertical position Fig. 25 (1) or in horizontal position Fig. (3) on the top of a sub-station on a tower or on one of the poles of the transmission line. The insulators 9 and 10 may be of any known or preferred type and may be mounted either 30 obliquely Fig. (1) or at substantially right angles Fig. (3) to the base 15 as desired, or may be mounted in inverted position if so desired.

Suitable socket terminals 16 and 17 (Fig. 35 3) are adapted to be mounted upon the terminal bases 2 and 3. The line wires 18 are suitably secured in these socket terminals.

The movable part of the particular switch shown comprises blades 19 and 20 of the 40 truss type, although this is immaterial in so far as my invention is concerned. The blades 19 and 20 are clamped at one end to the hinge jaws 4 by means of a bolt 21 and a pair of spring washers 22, which maintain 45 a uniform spring pressure upon the blades to hold them against the sides of the jaws 4. A spacing sleeve 23 is arranged upon the shank of the bolt 21 between the jaws 4 to maintain the parallel spaced relation of 50 these jaws.

The outer ends of the blades 19 and 20 are held together and firmly against the opposite sides of the terminal lug 1 through suitable spring washers by means of bolts 55 24 and 25. Guide members 26 provided adjacent each side of the terminal 1 guide the blades 19 and 20 over the end of the terminal. Such guide members are of particular utility in connection with switches having relatively 60 long blades such as the particular switch shown has; where slight play at the hinge terminal will frequently result in the blade swinging out of line with the other terminal. These guide members 26 are secured to the 65 terminal base 2 as by means of suitable

bolts 27. The blades 19 and 20 are maintained in proper spaced relation throughout their length by means of suitable channelled spacing pieces 28 interposed therebetween.

In order to assist in the breaking of the 70 arc in case the switch is opened when current is flowing through the conductors a horn 29 is mounted on the terminal base 2 adjacent the end of the blades 19 and 20. This horn 29 co-operates with a horn 30 mounted upon the end of the blades 19 and 20 to break the arc as well understood by those skilled in the art.

The switch is operated by means of a movable insulator 32, mounted between the insulators 9 and 10. The outer end of the insulator 32 is provided with an insulator clamp 33 having a tongue 34 extending therefrom. An arm 35, the lower forked end of which is pivoted at 36 to the angle 85 bracket 6, is pivotally connected at its opposite forked end as shown at 37 to the tongue 34. The upper end of the pivoted arm 35 is provided with a switch blade engaging shoe 38. The switch blade engaging 90 shoe or member 38 is adapted when the arm 35 is swung about its pivot 36 as will be hereinafter described, to engage the blades 19 and 20 forcing these blades to the open position about the shank of the hinge 95 bolt 21.

When the arm 35 is swung in a clockwise direction about its pivot 36 as will be described the blades 19 and 20 are returned to the closed position by means of a pair of links 100 40 pivoted at 37 to the tongue 34 and arm 35. The opposite end of the links 40 are mounted upon the shank of a bolt 41, extending between the switch blades 19 and 20. A spacing sleeve 42 arranged upon the bolt 41 between the links 40 serve to maintain these links in proper spaced relation.

The inner end of the insulator 32 is adjustably mounted upon a threaded stem 43. An arm 44 is rigidly secured upon the operating shaft 45 by means of a set bolt 46 and is thereby adapted to rotate in unison with this shaft. The free end of the arm 44 is pivotally connected as at 47 to the inner end of the threaded stem 43. The switch operating shaft 45 is mounted in suitable bearing members 48, bolted or otherwise suitably secured to the mounting base 15.

The mechanism for rotating the shaft 45 comprises an arm 50, fixed thereupon as by 120 means of a suitable set bolt 51 (Fig. 4). The free end of the arm 50 is pivotally connected at 52 to a forked connecting piece 53. An operating rod 54 mounted in the lower socketed end of the connecting piece 53 extends 125 to convenient position at the foot of the supporting structure and is there secured in a socketed lever arm 55. The lower end of the lever arm 55 is pivoted at 56 between a pair of spaced lugs 57 formed integral 130

with and extending from an operating lever 58.

The upper free end of this operating lever 58 is provided with a suitable operating handle 59. The operating lever 58 is pivotally mounted upon a pin 60 journaled at its opposite ends in suitable bearings 61 which bearings are preferably formed integral with a housing 62. The housing 62 comprises side 10 and top walls for protecting the auxiliary switching elements to be hereinafter described against various weather conditions and a mounting base 63 whereby the entire housing is mounted in a convenient position 15 at the foot of the supporting structure.

It will be noted that the lever arm 55 is curved just above the pivot pin 56 in such a manner as to enable this lever arm to engage around the pivotal center 60 of the operating 20 lever 58 when the same is swung downwardly (as illustrated in dotted lines in Fig. 3), whereby the operating lever may be swung through approximately 180 degrees. In this manner the operating lever 58 is 25 made self locking in either its upper or lower position, so that any longitudinal stress in the operating rod 54 resulting from any tendency of the switch to change position is positively resisted by the automatic locking 30 function of the operating lever 58. This is of importance in either the vertical or horizontal type of switch for the reason that the weight of the switch blade might otherwise tend to open or close the switch accidentally. 35 The lower pivoted end of the operating lever 58 is provided with a pair of diametrically opposite lugs 64 and 70 having suitable openings 65 formed therethrough for locking the operating handle and consequently 40 the movable switch element in either closed or open position as will be described later.

A sleeve 66 provided with a contact arm 67 and a pair of fingers 68 and 69 adapted for coöperation with the lugs 64 and 70 respectively is arranged upon a pin 71, journaled at its opposite ends in the sides of the housing 62. The contact pin 81 is normally held in contact with the spring contacts 72 by means of a spring 90 being swung out of 50 contact with the contacts 72 and into co-operation with contacts 73 against the tension of the spring 90 by the coöperation of the lug 64 with the finger 68 as will be hereinafter described. The spring 90 thus maintains engagement of the contact pin 81 with the contacts 72 until the switch is completely opened, whereupon this contact is broken and the lower of the lamps 80 (Fig. 5) is lighted, indicating that the switch is open. 55

60 The fingers 68 and 69 are not arranged in the same vertical plane but are arranged so that the lug 70 carried by the lever 58 will upon rotation of the lever avoid the lug 68 and coöperate with the lug 69 to swing the 65 contact arm 67 in a counter clockwise direc-

tion about the pin 71. Upon swinging the lever 58 in the opposite direction the lug 64 will avoid the finger 69 and coöperate with the finger 68 to swing the contact arm 67 in a clockwise direction about the pin 71. 70

Two sets 72 and 73 of spring contact members having coöperating terminal sockets 74 and 75 are mounted upon a base 76 of insulation, which base of insulation 76 is in turn mounted upon the mounting base 63 of the 75 housing 62. Conductors 78 having suitable sources of current 79 and lamps 80 interposed therein are connected across each set of terminal sockets 74 and 75 respectively.

The two lamps thus provided are made 80 distinctive preferably of distinctive colors in order that when the contact pin 81 carried by the contact arm 67 is bridged for example across the spring contact member 72 as shown in Fig. 4, the color of the lamp 85 lighted thereby will indicate to the operator the exact condition of the switch, namely as to whether the movable switch element is in the open or closed position.

The opposite side walls of the housing 62 90 are provided with openings adapted to register with either of the openings 65 provided in the lugs 64 and 70, which of these openings depending of course upon whether the switch is in the open or closed position. 95 When in the position shown in Fig. 4 a headed bolt 85 shown in dotted lines in Fig. 5 is adapted to be inserted through the registering openings provided in the lug 70 and in the side walls of the housing 62 respectively. The opposite end of the bolt 85 is provided with a transverse aperture through which the bow of a suitable padlock is adapted to be inserted to securely lock the operating lever 58 against rotation. 100 105

To operate the switch assuming the blades 19 and 20 to be in the closed position as shown in Fig. 1, the padlock 86 shown in dotted lines in Fig. 5 is removed, allowing the locking bolt 85 to be withdrawn. The 110 handle 59 is then grasped and the operating lever 58 is revolved in a counter clockwise direction about the axis of the pin 60. The lug 57 and the pivotal connection 56 are thus revolved about the pin 60 moving the operating rod 54 downwardly. This downward movement of the rod 54 causes rotation of the shaft 45 through the pivoted arm 50. The arm 44 affixed upon the shaft 45 is thereby rotated in unison therewith moving the 115 insulator 32 forwardly. This forward movement of the insulator 32 is adapted through the connection 37 to swing the arm 35 about its pivot 36 forcing the blade engaging shoe 38 carried by this arm into engagement with the blades 19 and 20. Further movement of the shoe 38 forwardly forces the blades 19 and 20 quickly and positively into open position about the hinge bolt 21. 120 125

It is a well known fact that if a discon-

necting switch remains closed for a long while opening of the same becomes very difficult. In the event that the switch is mounted upon insulators as in the present 5 instance, it will be apparent that under such conditions considerable strain must be necessarily placed on the insulators in order to open the switch through suitable operating mechanism from a distance. The operating 10 mechanism shown was designed to overcome just such difficulties. The supporting and operating insulators of the switch are in direct tension or compression when the switch is operating. There are no torsional 15 stresses to which such insulators have been commonly subjected heretofore. Obviously, this is a distinct advantage as a porcelain insulator for example is able to withstand a much greater stress in tension or compres- 20 sion than in torsion.

Upon initial movement of the operating lever 58, that is, upon initial opening of the switch, power is applied through a lever of considerable length, *i. e.*, from the hinge bolt 25 21 to the point of contact A of the shoe 38 with the blades 19 and 20. Thus a relatively great force is applied in breaking contact between the blades 19 and 20 and the terminal lug 1, insuring positive opening of the 30 switch. Upon breaking contact—thereafter only sufficient force being necessary to overcome the friction of the hinge clips—the power is applied through a relatively short lever arm corresponding to the sine of angle 35 21, 37, 41 or the sine of angle B, giving great speed to the switch blades, which is very vital in breaking the electric arc between the horns 29 and 30.

Upon initial movement of the operating 40 lever 58 the blades are positively forced out of contact with the terminal lug 1 through the shoe 38, which shoe 38 engages the switch blades 19 and 20 substantially intermediate the terminal lugs 1 and 4, the pin 41 sliding 45 through the slots C provided in the links 40, until the blades leave the terminal lug 1. Upon this positive breaking of contact the point of force is transferred over to the links 40 and pin 41 providing a much shorter 50 lever and correspondingly much higher speed of the blades 19 and 20.

When the blades have been revolved to full open position the aperture 65 in the lug 64 is adapted to register with the apertures provided in the side walls of the housing 62, whereupon the locking bolt 85 may be arranged therethrough and the padlock 86 inserted to securely lock the switch in open position. When in this position the 60 contact pin 81 is bridged across the spring contacts 73 and a lamp 80 lighted thereby to indicate to the operator that the switch is in open position.

Upon removing the locking bolt 85 and 65 swinging the lever 58 in a clockwise direc-

tion about the pin 60 the blades 19 and 20 are swung into engagement with the upper terminal lug 1 through the links 40.

While I have described my invention in connection with the details of a particular embodiment I do not intend thereby to limit the invention to such details as I am aware and contemplate that modifications and changes may be made without departing from the invention which is set out in the appended claims.

I claim:

1. In combination, a movable switch member, a pivot terminal for said member, a contact terminal for said member and means 80 engageable with said movable switch member within its length for forcing said member out of engagement with said contact terminal, said means remaining in engagement with said switch member for only a part 85 of its motion.

2. In combination, a movable switch member, a pivot terminal for said member, a contact terminal for said member, means engageable with said movable switch member 90 within its length for forcing said member out of engagement with said contact terminal, automatic means for locking said movable switch member in either open or closed position and means remote from said movable switch member for indicating as to whether said member is in open or closed position.

3. In combination, a movable switch member, a pivot terminal for said member, a contact terminal for said member, means engageable with said movable switch member within its length for forcing said member out of engagement with said contact terminal, said means separating from coöperating 105 engagement with said switch member at a predetermined position of the latter, and a shaft for actuating said means from a distance, said shaft having connection with a pivoted operating lever.

4. In combination, a movable switch member, a pivot terminal for said member, a contact terminal for said member, means engageable with said movable switch member within its length for forcing said member 115 out of engagement with said contact terminal, a shaft for actuating said means from a distance, said shaft having connection with an operating lever, said operating lever controlling an auxiliary switching element 120 for indicating as to whether the switch is in open or closed position and automatic means associated with said operating lever for locking said switch in either of said positions.

5. In combination, a movable switch member, a pivot terminal for said member, a contact terminal for said member and an operating mechanism whereby power is applied at one point of said switch member to 130

break contact between said movable switch member and said contact terminal and thereafter applied at a different point of said switch member to increase the speed of said 5 movable switch member toward full open position.

6. In combination, a switch having a movable switch member, a shaft adapted for rotation, a plurality of links having connection with said shaft whereby upon initial rotation of said shaft the switch will be opened by means of a force applied at one point of said switch member, further rotation of said shaft causing a force to be 10 applied to said movable switch member at a different point to increase the speed thereof.

7. In combination, a movable switch member, a pivot terminal for said member, a 20 contact terminal for said member, a pivoted lever adapted for coöoperating with said movable switch member to break contact between said member and said contact terminal, and a link connection between said 25 pivoted lever and said movable switch member through which said movable switch member is thereafter swung about said pivot terminal at an increased speed.

8. In combination, a movable switch member, a pivot terminal for said member, a contact terminal for said member, a pivoted lever adapted for coöoperating with said movable switch member to break contact between said member and said contact 30 terminal, a link connection between said pivoted lever and said movable switch member through which said movable switch member is thereafter swung about said pivot terminal at an increased speed, a shaft 35 adapted for rotation, a link connecting said shaft and said pivoted lever, an operating lever for rotating said shaft from a distance and means associated with said operating lever for indicating as to whether 40 said movable switch member is in open or closed position.

9. In combination, a movable switch member, a pivot terminal for said member, a contact terminal for said member, a shaft 50 adapted for rotation, means having connection with said shaft for moving said movable switch member out of coöperation with said contact terminal upon rotation of said shaft, means for indicating as to whether 55 said movable switch member is in open or closed position and means for automatically locking said first named means against accidental motion for locking said switch member in either of said positions.

60 10. In combination, a switch having a movable switch member, a shaft adapted for rotation, connections between said shaft and said movable switch member for operating said member upon rotation of said 65 shaft, an operating lever for rotating said

shaft from a distance, said operating lever being movable over dead center for locking said operating lever in open or closed position, said operating lever controlling an auxiliary circuit for indicating the position 70 of said movable switch member.

11. In combination, a switch having a movable switch member, means for moving said movable switch member into open or closed position, said means having an operating shaft, said shaft having connection with an operating lever and automatic means associated with said operating lever for locking said switch in either open or 75 closed position.

80 12. In combination, a movable switch member, a contact terminal for said member, a pivoted operating lever for actuating said switch member, said operating lever being movable into or over its dead center 85 positions for automatically locking said lever and said switch member against accidental opening or closing of said switch member.

13. In combination, a movable switch 90 member, a contact terminal for said member, remote control mechanism situated at a point remote from said switch member and adapted to actuate the latter, said remote control mechanism comprising a manually operated pivoted handle, a rod extending from said handle and having operative connection with said switch member, said handle being movable into or through two diametrically opposite dead 95 center points for positively locking said movable switch member against accidental movement into either open or closed position.

14. In an electrical switch, switch terminals, a switch member adapted to connect said terminals, an operating mechanism engageable with said switch member for forcing the same into open position, said operating mechanism separating from operative 100 connection with said switch member after the initial opening motion of the latter, connections between said switch member and said operating mechanism for closing the switch, said operating mechanism controlling an auxiliary switching element for 105 indicating as to whether said switch member is in open or closed position.

15. In an electrical switch, switch terminals, a switch member adapted to connect 110 said terminals, an operating mechanism engageable with said switch member for forcing the same into open position, said operating mechanism and said switch member separating after the initial opening motion 115 of the latter, connections between said switch member and said operating mechanism for closing the switch, actuation of said operating mechanism controlling an auxiliary switching element for indicating 120 125 130

- as to whether said switch member is in open or closed position, and means associated with said operating mechanism for locking said switch member in either of said positions. 5
16. In combination, a pair of insulators, clamps mounted on said insulators, brackets supported on said clamps, switch terminals on said brackets, a pair of switch blades 10 pivoted to one of said terminals, a lever pivoted to one of said brackets at a point eccentric to the pivot point of said switch blades, said lever being engageable with said switch blades and means for swinging 15 said lever into coöperation with said blades to open the switch. 16
17. In combination, a pair of insulators, clamps mounted on said insulators, brackets supported on said clamps, switch terminals 20 on said brackets, a pair of switch blades pivoted to one of said terminals, a lever pivoted to one of said brackets at a point eccentric to the pivot point of said switch blades, said lever being engageable with said switch 25 blades, a shaft for actuating said lever from a distance and means for indicating as to whether the switch is in open or closed position. 25
18. In combination, a pair of stationary 30 switch terminals, a movable switch member pivoted to one of said terminals and adapted for coöperation with the other of said terminals, a movable insulator mounted between said terminals, a shaft for actuating said insulator from a distance, a blade engaging member on said insulator adapted to impart a large opening force to said movable switch member to force said member quickly and positively into contact breaking 35 position, and independent means for completing the opening motion of said switch member. 40
19. In combination, a switch having a movable switch member, a pivoted lever 45 adapted for coöperating with said movable switch member to open the switch, means for actuating said pivoted lever, said pivoted lever separating from coöperative engagement with said switch member, and means 50 connecting said movable switch member and said pivoted lever, whereby said movable switch member may be returned to closed position. 55
20. In combination, a movable switch member, a pivot terminal for said member, a contact terminal for said member, a rocking insulator adapted for coöperating with said member to swing the same about said pivot terminal, an operating lever for controlling 60 said rocking insulator from a distance, means for indicating as to whether said movable switch member is in open or closed position, and automatic means associated with said operating lever for locking 65 said member in either of said positions. 65
21. In a mechanical movement, the combination of a pivotally swinging member required to have a motion of variable force and velocity applied thereto, a driving arm transmitting a driving force to said swinging member at one point of the latter during a predetermined part of the motion of said swinging member, and means coöperating with said swinging member and said driving arm for transferring the point of application of the driving force between said driving arm and said swinging member during a second predetermined part of the motion of said swinging member. 70
22. In combination, a movable switch member, a contact terminal for said member, switch operating mechanism comprising a member adapted to exert a relatively large switch opening force at a relatively long radius during the initial motion of said switch member, and a link connecting said member with a point of relatively shorter radius for thereafter transmitting an increased velocity to said switch member. 80
23. In combination a pivoted switch member, a contact member for said pivoted switch member, a driving arm and means for applying a relatively great leverage from said driving arm to one point of said pivoted switch member to break contact between said member and said contact terminal and thereafter a decreased leverage at another point of said switch member for increasing the speed of said pivoted switch member. 90
24. In an electrical switch, the combination of a contact terminal, a movable switch element coöperating therewith, and switch operating mechanism comprising means exerting a relatively large force upon said movable switch element during the initial part of this motion, and a relatively large velocity during the remaining part of its motion, said switch operating mechanism imparting a high velocity motion to said movable switch element through a radius arm of increasing radius. 105
25. In a switch, a movable switch member and a contact terminal coöperating with said member, a switch operating arm pivoted eccentrically to said movable switch member, means for actuating said operating arm, said arm transmitting a switch opening force to said switch member at one point during one part of the motion of said switch member, and transmitting an accelerated motion to another point of said switch member during a second part of the motion of said switch member. 115
26. In a switch, a movable switch blade, a stationary hinge terminal upon which said blade is pivoted, a contact terminal for coöperation with said blade, a switch operating arm pivoted eccentrically to the pivot of said switch blade, said operating arm trans- 125
- 130

mitting a relatively large force to said switch blade by engagement therewith, and means connecting said operating arm and said switch blade for transmitting an accelerated motion to said switch blade during a predetermined part of its throw.

27. In an electrical switch, the combination of a contact terminal, a movable switch element, and switch operating mechanism comprising means exerting a relatively large force upon said movable switch element during the initial part of its motion, and a relatively large velocity during the remaining part of its motion, an operating insulator connecting with said operating mechanism, and means for transmitting motion through said insulator in such manner that said insulator is not subjected to torsion or lateral breaking stresses.

28. In an electrical switch, the combination of a contact terminal, a movable switch element, a switch operating member for imparting a relatively powerful contact breaking force to said switch element, a link connecting said operating member with said switch element for transmitting an accelerated motion thereto during a predetermined part of the throw of said switch element, an operating insulator connecting with said operating member, and means for transmitting operating motion through said insulator substantially longitudinally thereof to avoid torsion and lateral breaking stresses in said insulator.

In witness whereof I hereunto subscribe my name this 27 day of May, A. D. 1919.

CHRISTEN CHRISTENSEN.
